UNITED STATES PATENT OFFICE.

LOUIS M. POTTS, OF HIGHWOOD, NEW JERSEY, ASSIGNEE TO WESTERN ELECTRIC COMPANY, INCORPORATED, OF NEW YORK, N. Y., A CORPORATION OF NEW YORK

TELEGRAPH SYSTEM.

Application filed January 5, 1922. Serial No. 527,064.

To all whom it may concern:

Be it known that I, Louis M. Potts, a citizen of the United States, residing at Highwood, in the county of Bergen, State of New Jersey, have invented certain new and useful Improvements in Telegraph Systems, of which the following is a full, clear, concise, and exact description.

This invention relates to telegraph systems and particularly to current impulse repeaters for use in such systems.

An object of the invention is the provision of an efficient, reliable, and inexpensive repeating means whereby signaling impulses may be repeated from one line section to another free from bias and distortion.

The invention is an improvement of the system disclosed and claimed in P. M. Rainey's Patent No. 1,530,514, granted Mar. 24, 1925.

The invention provides a single vibrating member having a natural period of motion in combination with a plurality of polarized-storing relays for repeating, free from bias and distortion, signaling current impulses transmitted from two distant stations.

The drawing shows one embodiment of the invention.

Line conductors 4 and 5 extend from distant stations which are equipped for sending and receiving messages simultaneously. Connected with the conductor 4 in series are polarized relays 6 and 7. Relay 6 controls the operation of a neutral relay 8 through the discharge of condensers 30 and 31. Relay 8, in turn, controls mechanism for governing a tuning fork 9 or other vibrating member which has a natural period of motion corresponding to the frequency of the impulses transmitted over the line conductors. This mechanism comprises a neutral relay 19, a relay 10, and a magnet 11 which is energized by a circuit extending from the positive terminal of battery 22 through a resistance 23, the winding of magnet 11, an extension of one prong of the fork, and a contact 29, to the negative terminal of battery 22. When the armature of relay 10 is in the position shown, the resistance 23 is short circuited through this armature and its contact.

The tuning fork in vibrating forms a contact alternately with the positive and negative contacts of a battery 22 and thus energizes polarized relays 12, 13, and 14. Relay

13 controls relay 19, which in turn controls through its contacts the energizing circuit of relay 10. Relay 12 controls a relay 15 whose armature connects the line conductor 5, extending to the ratio arms in bridge of which the windings of a receiving relay 3 corresponding to relay 7 are connected, with the batteries connected with polarized storing relays 17 and 18 alternately. Relay 12 also controls a relay 16 whose armature connects the relay 7 with storing relays 18 and 17 alternately. Controlled by relay 14 are relays 25, 26, 27, and 28 which correspond to relays 15, 16, 17 and 18, respectively, and which operate in conjunction with the line conductor 5 and relay 3 for repeating signaling impulses from the line conductor 5 to the apex of the ratio arms in bridge of which relay 7 is connected.

Let it be assumed that the tuning fork 9 is vibrating in unison with the frequency of impulses sent over the line conductors, and that an impulse of negative polarity has been applied to the line conductor 4, putting the armatures of all the relays controlled thereby in the position shown in the drawing. Let it be further assumed that an impulse of a positive polarity is transmitted over the line conductor 4, and that this impulse reverses the position of the armatures of relays 6 and 7. When the armature of relay 6 is reversed, current flows momentarily through relay 8, which momentarily attracts its armature, sending an impulse through either the upper or the lower coil of relay 10, depending on the position of the armature of relay 19. If the lower coil of relay 10 is energized, the armature remains in the position shown, the resistance 23 is short circuited through the armature and contact of relay 10, and, the lower prong of the tuning fork being in contact with contact 29, the magnet 11 is energized. If the upper coil of relay 10 is energized, the armature is reversed, this circuit is broken and the current flowing through the resistance 23 when the tuning fork establishes a contact with the contact 29 does not energize the magnet. The upper coil of relay 10 is only energized when the relay 19 attracts its armature, and this is controlled by the tuning fork 9, as explained below.

As the prongs of the tuning fork vibrate outwardly its upper prong establishes a contact with the upper contact of a battery 22. At the same time its lower prong establishes

a contact with contact 29; thereby energizing the magnet which acts to make the fork vibrate inwardly, so that its upper prong establishes a contact with the lower contact of the battery 22. The circuit through the magnet having been broken at 29, the magnet will be deenergized and the fork will then tend to vibrate outwardly again. As the upper prong of the fork makes connections alternately with positive and negative contacts of battery 22 it causes current to flow through the windings of relay 12, 13 and 14 for reversing the position of their armatures. Connected with the contacts of relay 13 and a source of battery are condensers 20 and 21 which upon discharging send impulses of momentary duration through relay 19. If the tuning fork is vibrating in perfect coordination with the frequency of the incoming signals, relay 19 and the upper coil of relay 10 will be energized at the exact instant that an impulse from line conductor 4 is received so that no circuit will be established through the armature and contact of relay 10, and the magnet will only be normally energized. If the vibrations of the tuning fork are not in coordination with the incoming signals, however, the armature of the relay 19 will be in the position shown when an impulse is received from line conductor 4, the resistance 23 will be short circuited, and the magnet will be strongly energized when a contact is established at 29, and will function to coordinate the vibrations of the tuning fork with the signals received over the line conductor 4.

Assume, as before, that the device is in operation, that the armatures of the relays of the system are in the position shown, and that it is desired to repeat from the line conductor 4 a signaling impulse of a positive polarity which will be free from bias and distortion to the line conductor 5. The signaling impulse of a positive polarity impressed at the end of the line 4 being received at the repeating station passes through the windings of the polarized relays 6 and 7 thereby causing the reversal of the position of their armatures. Relay 6, in reversing the position of its armature, breaks the circuit through relay 8 and condenser 31 and allows this condenser to be charged. It establishes a circuit through relay 8 and condenser 30, and this condenser, in discharging, allows an impulse to flow momentarily through relay 8. As shown above, however, this relay only affects the vibrations of the tuning fork when it is not vibrating in unison with the signals being transmitted over the line 4. Relay 7, in reversing the position of its armature, applies positive battery to the winding of polarized relay 17, the energizing circuit of which extends from the positive terminal of battery, upper contact and armature of relay 7, armature and contact of relay 16, and the windings of relay 17, to the negative terminal of battery. Relay 17 reverses the position of its armature for connecting positive battery with the upper contact of relay 15; and, since this relay is controlled, as previously described, from contacts on the polarized relay 12, which in turn is controlled by the contacts of the tuning fork, this relay will thus be operated in unison with the transmitted signals. The relay 15 will also be caused to reverse the position of its armature for connecting to the apex of the ratio arms, in bridge of which the receiving relay 3 is connected, the positive terminal of the battery controlled by the armature of relay 17. An impulse of a positive polarity will thus be transmitted over the line conductor 5 to the distant station connected thereto.

Owing to the effect of line lag it is necessary to control the energization of relays 15 and 16 so that these relays will be energized at the time signals are received at the repeating station or shortly thereafter, by the use of a variable inductance 24. This inductance may be varied over a wide range for controlling the energization of relays 15 and 16 through contacts under the control of relay 12.

Similarly, signaling impulses transmitted over the line conductor 5 may be regenerated and repeated to the line conductor 4 free from bias and distortion simultaneously with the transmission of signaling impulses from the line conductor 4 to the line conductor 5, as previously described.

Inasmuch as relays 12 and 14 operate simultaneously, the relays connected therewith must operate simultaneously with each other under ultimate control of the signals over the line conductor 4. The signals repeated over line conductors 4 and 5 are thereby coordinated.

While a specific way of arranging telegraph apparatus according to this invention has been shown, it is to be understood that the invention is not limited to this particular arrangement.

What is claimed is:

1. Repeating apparatus connected intermediate two adjacent line sections extending to remotely situated stations comprising a plurality of polarized relays controlled by impulses received from one of the line sections for storing such impulses which are to be subsequently retransmitted over the other line section, and a member having a natural period of motion cooperating with said relays for effecting the retransmission of the impulses stored in said relays.
2. In a telegraph system, a line equipped for duplex operation; a repeater associated with said line comprising a plurality of relays controlled by incoming impulses for effecting the storage of said impulses which

are later to be retransmitted, and a member having a natural period of motion cooperating with said relays for effecting the retransmission of impulses stored in said relays in both directions simultaneously over said line.

3. In a telegraph system, a line equipped for duplex operation and divided into sections, a repeater connected intermediate the sections of said line comprising a plurality of relays controlled by incoming impulses from one of said line sections for storing the impulses which are later to be retransmitted to the other line section, a vibrating member having a natural period of motion cooperating with said relays for effecting the retransmission of said impulses free from bias and distortion, and means for coordinating the vibration of said member with the frequencies at which impulses are being transmitted over said line.

4. In a telegraph system, a line conductor equipped for duplex service, a repeater connected intermediate the ends of said line conductor comprising a single vibrating member having a natural period of motion equal to the frequency at which signals are being transmitted over the line, a source of signaling current, a plurality of polarized storing relays controlled by said vibrating member for regenerating and repeating message impulses from one line section to another free from bias and distortion, and

means whereby vibrations of said vibrating member may be coordinate with the frequency at which signals are being transmitted over said line.

5. In a telegraph system a line conductor equipped for duplex service, a repeater connected intermediate the ends of said line comprising a member having a natural period of motion equal to the frequency at which signals are being transmitted over said line, means controlled by said member for storing and repeating free from bias and distortion from one line section to another the signals transmitted over said line, and means for maintaining the vibrations of said member in unison with the signals transmitted over said line.

6. In a telegraph system, a line conductor equipped for duplex service, a repeater comprising a vibrating member having a natural period of motion, two pairs of polarized relays connected with each line section for storing and repeating free from bias and distortion the signals transmitted over the line, said pairs of relays being controlled by said vibrating member, and means for coordinating the vibrations of said vibrating member with the frequency at which signals are being transmitted over the line.

In witness whereof, I hereunto subscribe my name this 3rd day of January A. D., 1922.

LOUIS M. POTTS.
